UNITED STATES PATENT OFFICE

143,597

DESIGN FOR A TOY CANNON

William E. Kanngiesser, Chicago, Ill.

Application October 31, 1944, Serial No. 116,073

Term of patent 3½ years

(Cl. D34—15)

To all whom it may concern:

Be it known that I, William E. Kanngiesser, a citizen of the United States, residing at Chicago, in the county of Cook and State of Illinois, residing at 1139 Hyde Park Boulevard, Chicago, Illinois, have invented a new, original, and ornamental Design for a Toy Cannon, of which the following is a specification, reference being had to the accompanying drawings forming a part thereof.

In the drawings,

Fig. 1 is a side elevational view of the toy can-

non in a firing position, showing my new design; Fig. 2 is a side elevational view of the toy cannon in a receded position;

Fig. 3 is a top plan view;

Fig. 4 is a front elevational view of the toy cannon in the position shown in Fig. 2; and

Fig. 5 is a front elevational view of the toy cannon in the position shown in Fig. 1.

I claim:

The ornamental design for a toy cannon, as shown.

WILLIAM E. KANNGIESSER.
